UNITED STATES PATENT OFFICE

WILLIAM G. LEAMON, OF NEWARK, OHIO

ART OF TREATING OILS

No Drawing.

Application filed August 26, 1925. Serial No. 52,687.

This invention relates to art of treating oils; and it relates more particularly to the treatment of mineral oils such as petroleum, petroleum distillates and residua, in the manufacture of valuable commercial products; and the invention also relates to novel compositions of matter employed in such treatment.

In prior co-pending applications Serial 10 Nos. 621,076 and 624,268, this applicant has disclosed and claimed various embodiments of a procedure which may be termed a modifying treatment of oils with the aid of a catalytic material functioning as a polymerizing 15 or condensing agent in such manner as to simplify removal of undesirable constituents from a given oil without necessarily effecting conversion of said oil in the sense of cracking. Among the treating agents disclosed in said prior applications as useful in thus improving mineral oils are solutions of aluminum chlorid or zinc chlorid in certain solvents differing from but miscible with the oil to be treated, among such solvents being ethyl ether (sulfuric ether), and nitrobenzene. Among the oils to which the aforesaid treatment is especially well adapted are gasolines and motor fuels generally of the gasoline type, particularly those derived by cracking heavier 25 oils. Kerosenes and lubricating oils, for example, may also be advantageously treated according to the new process.

As a result of further research in this field, it has been discovered that certain other 30 solvents to be mentioned hereinafter can be used with success in conjunction with catalytically acting metal halids, particularly metal chlorids such as aluminum chlorid, or zinc chlorid, or both, for the purpose of polymerizing or condensing resin- or gum-forming constituents contained in an oil which it is desired to purify or refine.

While the present invention is of broad 45 application in the treatment of oils to improve the same, its greatest present utility is in the treatment of crude motor fuel for the purpose of rendering the same stable, that is, to so treat it that the finished product will not undergo substantial changes in composition resulting in the formation and deposi-

tion of gummy or resinous polymers. It is a well-known fact that many commercial motor fuels of the gasoline type develop such deposits upon standing for time periods of greater or less length depending upon the particular 55 motor fuel. Furthermore, even where a motor fuel may not show a gummy or resinous deposit upon standing for a long time, such polymers may exist in solution and their presence become manifest when the fuel is used 60 in an engien, either through sticking of the valves or deposition of carbon in the cylinders. It is the elimination of these gum-forming constituents from mineral oils, specifically from motor fuel fractions, that forms 65 one of the principal objects of the present invention.

It has been found that a solution of either zinc chlorid or aluminum chlorid in ethyl acetate (acetic ether, $\text{CH}_3\text{CO}_2\text{C}_2\text{H}_5$) can be 70 used as the treating agent in a purifying or improving process of the character above described. Somewhat better results are obtained with zinc chlorid than with aluminum chlorid. The salts need not be strictly anhydrous but should contain only very little water, if any. Assuming the use of zinc chlorid, a saturated solution is made by adding an excess of commercial granulated or fused zinc chlorid to ethyl acetate. A vigorous 75 reaction takes place between the salt and the ethyl acetate indicating that the result is something more than a mere solution of the zinc chlorid in the solvent. In all probability a complex compound of zinc chlorid and 80 ethyl acetate is formed. In treating in accordance with the invention a crude motor fuel fraction derived from the cracking or conversion of a heavy mineral oil, for example, the zinc-chlorid-ethyl-acetate solution prepared as above described may be added to the motor fuel in amount equal in a typical 85 instance to about 0.25% by weight of the motor fuel to be treated. While this percentage may be varied somewhat in practice, it need not ordinarily exceed 0.50% as a rule and practically need never amount to as 90 much as 1%. The solution is readily miscible with the motor fuel and it diffuses rapidly therethrough even without agitation, al-

though agitation is often desirable to expedite distribution and the desired polymerizing reaction. The treatment may be effected at ordinary temperatures, but the reaction can be speeded up by moderate heating.

- 5 A precipitate of gummy polymers forms soon after the addition of the treating solution and settles rather rapidly. This precipitate can be separated by decantation or filtration, 10 and in some cases where the motor fuel is thus freed from this precipitate it can be used without further treatment. However, redistillation of the treated motor fuel in an ordinary re-run still is generally advisable, 15 especially where, as is often the case, the action of the treating solution forms polymers which are soluble in the motor fuel and therefore are not precipitated out with or as the gummy deposit or precipitate before 20 mentioned.

It is of course also possible to add the treating solution directly to a charge of the crude motor fuel fraction in a re-run still, either with or without the further addition of 25 fuller's earth, pumice, a silica-gel, or other granular adsorptive solid material, the addition of adsorptive material being advantageous for various reasons among which may be mentioned the fact that the precipitable gummy polymers and coloring matter 30 are precipitated upon and firmly held by such adsorbent material and are thus prevented from being deposited upon the bottom of the still where they might be subjected to drastic 35 overheating and decomposition with resultant bad effect upon the distillate produced.

It has also been found that a solution of aluminum chlorid in normal propyl alcohol can also be used effectively in some cases in 40 this general method of improving mineral oils, particularly motor fuel fractions of the gasoline type. In preparing such a treating solution, aluminum chlorid, for example, is added in excess to normal propyl alcohol and 45 a vigorous reaction ensues with production of a saturated solution. Here again the result is probably more than a mere solution and involves formation of an aluminum-chlorid-propyl-alcohol complex of some kind.

50 Excellent results can be obtained by using this treating solution in the proportion of about 0.25% by weight of the mineral oil to be treated, this proportion being capable of variation within reasonably wide limits but 55 not more than 0.5% by weight being ordinarily required, and practically never more than 1% as a maximum. Usually the polymers formed when using this solution are not precipitated but remain dissolved in the 60 oil, giving it a red or green color; but separation may be effected by redistilling. When too large an amount of the treating solution is used, say as much 2 per cent, the color of the distillate is darkened. Best results are obtained when the quantity of treating solu-

tion added to the oil to be treated is so limited that the color of the mixture does not go beyond a red and change to green.

In using ethyl acetate and normal propyl alcohol as solvents as above described, it is 70 not essential that they be anhydrous. A water content of 0.5% appears to be unobjectionable and in the case of propyl alcohol somewhat better results are sometimes obtained where a slight percentage of water of 75 this order of magnitude is present in the solvent, especially as regards attainment of somewhat better color in the finished motor fuel or other mineral oil to be treated. This 80 advantageous effect of the presence of a slight amount of water in the solvent has been observed also in preparing a treating solution by dissolving zinc chlorid in ethyl ether.

In still another embodiment of the broad invention, use may be made under proper conditions of certain solvents which, although capable of dissolving metal chlorids such as aluminum chlorid and zinc chlorid, and also miscible with oils, do not when employed alone yield with such chlorids solutions effective to treat oils in accordance with the principles of the invention. For example, if it be attempted to improve crude motor fuel by treatment with a solution of either aluminum chlorid or zinc chlorid in ethyl alcohol 95 alone, no useful result is obtained. The same is true when methyl alcohol is employed. If, however, an ether be incorporated in such a solvent, it is found that the resultant solution of metal halid is an active improving 100 agent in treating an oil. Thus, if dimethyl 105 oxid (dimethyl ether) prepared in any known or suitable manner, be passed into methyl alcohol in which zinc chlorid or aluminum chlorid has been dissolved, the result 110 is a limpid and highly fluid composite treating solution that may be effectively employed in the practice of the invention. In a typical 115 instance a saturated solution of zinc chlorid in methyl alcohol may be made up, and this in turn saturated with dimethyl ether to produce the final treating solution, which may then be employed for improving oils in the manner hereinabove described. It is especially 120 advantageous to use methyl alcohol in the form of synthetic methanol in preparing the ether-alcohol solution as described. It is also possible first to pass the dimethyl ether into the alcohol and then dissolve the metal chlorid in the composite solvent, but this 125 method of procedure is generally less satisfactory.

Etherizing an ethyl alcohol solution of a catalytic metal salt with dimethyl ether also yields treating solutions useful in practicing 130 the invention.

Methyl alcohol and ethyl alcohol solutions of metal salts may also be treated with ethyl ether to form ether-alcohol solutions of said salts which are active treating solutions with- 135

addition of methyl or ethyl ether to catalytic metal salt solutions which themselves already function as active treating solutions, has the effect of rendering such solutions substantially more active. Thus adding either methyl or ethyl ether to a propyl alcohol solution of aluminum chlorid gives a more active treating solution than when the salt is dissolved in propyl alcohol only. It is to be understood that in these cases also, the ether-alcohol solvent may be made up first and the salt then dissolved therein, but such procedure is less advantageous.

The action of any of the above-described treating solutions prepared by dissolving only zinc chlorid in a solvent can also be accelerated by adding thereto a solution of aluminum chlorid. Aluminum chlorid alone in a treating solution is sometimes rather more active than is convenient or desirable; but by adding a small proportion to a zinc chlorid solution, a distinct promoting or accelerating effect is produced and yet the action of the resultant combined solution is not too rapid or drastic but on the contrary is easily controllable and otherwise advantageous. For example, to a saturated solution of zinc chlorid in ethyl ether may be added a saturated solution of aluminum chlorid in ethyl ether or in propyl alcohol. The quantity so added may vary widely but in practice such additions of the aluminum chlorid solution may range from 1 to 10 per cent by volume of the zinc chlorid solution, but a range of from 2 or 3 to 5 per cent is usually amply effective.

The addition of a very small amount of an acid, such as sulfuric acid, or acetic acid, for example, to any of the treating solutions hereinabove described also has a promoting or accelerating effect upon its action. Only a trace of such acid in the solution is in most cases sufficient to produce the desired effect.

It is to be understood that the term "ether" as used herein includes not only the true ethers, but also the so-called "acetic ether".

What I claim is:

1. The process of improving a mineral oil containing gum-forming constituents which comprises subjecting the same to the polymerizing action of a solution of a catalytic metal chlorid in ethyl acetate.

2. The process of improving a mineral oil which comprises subjecting the same to the action of a solution of zinc chlorid in ethyl acetate.

3. The process of improving a mineral oil containing gum-forming constituents which comprises subjecting the same to the polymerizing action of a solution of catalytic metal halid in ethyl acetate.

4. The process of improving a mineral oil which comprises subjecting the same to the action of a solution of a catalytic metal halid in a solvent that comprises acetic ether and propyl alcohol.

5. The process of improving a mineral oil containing gum-forming constituents which comprises subjecting the same to the polymerizing action of a solution of a catalytic metal halid in a solvent that comprises acetic ether and an alcohol.

6. The process of improving a mineral oil containing gum-forming constituents which comprises subjecting the same to the polymerizing action of a solution of a catalytic metal halid in a solvent that comprises an ether and an alcohol.

7. The process of improving a mineral oil containing gum-forming constituents which comprises subjecting the same to the polymerizing action of a solution of a catalytic metal halid in an ether-alcohol solvent.

8. The process of improving a mineral oil containing gum-forming constituents which comprises subjecting the same to the polymerizing action of a solution of a catalytic metal halid in a mixture that comprises an ether and a solvent miscible with the oil to be treated.

9. The process as set forth in claim 7, further characterized by the fact that the catalytic metal halid employed is zinc chlorid.

10. The process of improving a mineral oil which comprises subjecting the same to the action of a solution comprising both zinc chlorid and aluminum chlorid in association with a mixed solvent that dissolves both and is miscible with the oil to be treated.

11. The process as set forth in claim 10, further characterized by the fact that the proportion of aluminum chlorid present in the treating solution is relatively small as compared to that of zinc chlorid.

12. The process as set forth in claim 10, further characterized by the fact that the treating solution comprises a mixture of a solution of zinc chlorid in an ether and a solution of aluminum chlorid in propyl alcohol.

13. The process as set forth in claim 7 further characterized by the fact that the treating solution also contains a small proportion of an acid accelerating agent.

14. The process as set forth in claim 7, further characterized by the fact that the mineral oil treated is a motor fuel, more particularly a crude motor fuel of the gasoline type produced by a cracking process.

In testimony whereof I hereunto affix my signature.
